UNITED STATES PATENT OFFICE.

KARL LANDGREBE, OF ENSLEY, ALABAMA.

TWYER-CAP.

1,129,993.

Specification of Letters Patent.

Patented Mar. 2, 1915.

Application filed September 29, 1914. Serial No. 864,185.

To all whom it may concern:

Be it known that I, KARL LANDGREBE, a citizen of the United States of America, residing at Ensley, in the county of Jefferson and State of Alabama, have invented certain new and useful Improvements in Twyer-Caps, of which the following is a specification.

My invention relates to twyer caps for blast furnaces and like devices. Heretofore, such caps have been provided with a single centrally disposed hole over which a plug of various design is fitted and in this plug is fitted a glass through which the movement of the stock inside may be seen. When it becomes necessary to "rod-out" or clean a twyer, its plug is removed and a bar inserted through a common sight and clean out hole to poke out cinder which may be lodged at the nose of the twyer. Periodically, the plug has to be removed to clean dust from front of glass. Both "rodding out" and cleaning glass is done while blast is on the furnace and is attended with a considerable loss of wind and objectionable noise, and some danger from hot dust to the eyes of the operator. Also the central arrangement of the hole, which is necessary to give the right elevation for a peep sight into the furnace, makes it difficult to draw out through it the dust, etc., which accumulates or is forced there by the blast in cleaning the twyer.

According to my invention, the twyer cap is provided with two openings, one, a large or "poking" hole disposed near the bottom level of the blow stock, and the other a small peep hole normally closed by a peep plug and disposed in the upper part of the cap. This would prevent any substantial loss of air during cleanings of the peep glass and would require the larger hole to be opened only at long intervals when the twyers have to be cleaned.

As a further improvement on the general design of my invention and to increase its factor of safety, I have arranged the sight plug with its peep hole eccentric to its axis of rotation so that by turning the plug the hole may be moved out of register with the hole in the plug seat in the cap, thereby shutting off the air from the sight glass and permitting it to be removed, cleaned and replaced without loss of air or danger to the operator, after which the plug can be restored to operating position.

My invention further comprises the novel details of construction and arrangements of parts which are hereinafter more particularly described, but only in their preferred embodiment which may be materially altered within the scope of my invention.

I have illustrated one embodiment of my invention in the accompanying drawings, in which:

Figure 1 is a plan view of the twyer cap in closed position on its seat. Fig. 2 is a front elevation of Fig. 1. Fig. 3 is a vertical sectional view taken on the line $x-x$ of Fig. 2.

In the illustration of my invention I have omitted as unnecessary any parts of the furnace bosh and have shown my improved cap 1 applied to close the outer end of the penstock or blowstock 2, which is provided at its outer end with a twyer cap seat 3 of ordinary construction, having on opposite sides pairs of lugs 4, 4, and 5, 5. Between the lugs 4 I pivot, by means of a pin 6, an eye bolt 7, the outer threaded end of which is passed through a bolt hole in the side extension 8 of the cap and receives a nut 9 which connects the cap to the bolt 7 as a hinge. An eye bolt 10, similar to 7, is pivoted by a pin 11 between the ears 5 and its outer threaded end is adapted to swing between the jaws 12 on the cap 1 diametrically opposite to the extension 8. A nut 13 is threaded on the outer end of bolt 10 and when it stands between the jaws, can be screwed down to draw the cap tightly into place against its seat 3. The inner face of the cap 1 has a raised central annular shoulder 14 which fits into the opening in the seat 3 and a machined face 15 which abuts the outer face of the seat.

The twyer cap is provided with a clean out hole 16 which extends through the plate near the lower edge of shoulder 14 and has its outer end enlarged to form a seat for a stopper 17. This stopper is provided with a shank 18 which is pivotally connected by a bolt 19 to a handle 20. The handle is pivoted at one end between the bifurcations of a stud 21 having a threaded shank which is screwed into a threaded opening tapped into the cap. The handle at its outer end is received between the bifurcations of a stud 22 which have alining slots 23 therein adapted to receive a taper pin 24 by means of which the handle is forced inwardly and

locked to hold the stopper against its seat and seal the hole 16. The handle is provided with slotted enlargement 25 at its center through which the shank 18 of the 5 stopper 17 passes and is pivotally held therein by a bolt 19. Near the upper end of the cap I provide a sight plug seat 26 which is bored thereinto at a slight angle to the face of the cap plate so that it slopes 10 upwardly and inwardly at a small angle. This seat 26 is threaded except at its inner end. A sight plug 27 has its inner end flanged at 28 and adapted to turn with a smooth air tight joint against the bottom 15 of the seat 26, the plug being held therein by means of a stud 29 which has external screw threads adapted to screw into the seat 26 and which is provided with a smooth center bore which will receive and turn freely 20 about the sight plug 27. The outer enlarged end of the stud 29 is squared to receive a wrench. The outer end of the plug is threaded and adapted to receive a pipe cap 30 which is intended to hold in place 25 over the end of the plug a blue sight glass 31. The cap has a central sight opening 32. A sight hole 33 is bored diagonally from end to end through the sight plug, its inner end being eccentric to the long axis 30 of the plug. The inner wall of the seat 26 is provided with a sight hole 34, also arranged eccentrically therein and in position to register with the plug hole 33 when the sight plug has been turned to its operating 25 position. The seat is bored in at an angle corresponding substantially to the angle at which the sight hole 33 is bored in the plug, this arrangement bringing the hole 33 in horizontal alinement with the holes 32 and 34 when in sighting position. The hole 33 thereof will move out of register with the hole 34 which will then be closed by the inner end of the plug which is turned smooth 40 to serve as a valve and by this means the air pressure is shut off from the plug, thereby permitting the cap 30 to be removed and the glass cleaned or replaced leisurely and without risk to the operator. The arrangement described for bringing the inner end of the 45 sight hole 33 to a point eccentric to the long axis of the plug is merely a preferable arrangement and may be varied if desired, the object being to obtain in one position of the sight plug a sight opening through 50 which the stock inside the furnace may be seen, the continuity of which opening may be broken by shifting the plug and shutting off the air pressure from the glass and its retaining means. Any other suitable means 55 than that described may be used to plug the clean out hole 16, and its arrangement near the bottom of the blow stock is desirable in that on the removal of the plug for "rod-ding-out" the twyers, the blast will carry 60 out with it the cinders and dust and not 65

leave an accumulation below the hole where it tends to accumulate with the present twyer caps.

What I claim as new and desire to secure by Letters Patent, is:—

1. The combination with a twyer, of an end cap therefor having two holes therein, one hole being a large clean out opening near the lower part of the cap and the other being a small sight opening in the upper part 70 of the cap, a closure for the clean out hole, and a sight plug for the sight opening which is independent of the closure for the clean out hole, both said holes giving access to the twyer in the direction of its length, substantially as described. 75

2. A cap for twyers and like devices having a large clean out hole and a small sight hole above the clean out hole, a stopper for the clean out hole, fastening means for the stopper, a sight plug mounted over the sight hole and having a sight opening therethrough adapted, in a predetermined position of the plug, to register with the sight hole in the twyer cap, means to adjust said 80 sight plug to move its opening out of register with the sight hole in said cap, a glass for the opening in the sight plug, and detachable means to hold said glass in place, substantially as described. 85

3. In a twyer cap having a clean out hole and a relatively small sight hole, a closure for the clean out hole, a sight plug mounted in front of the sight hole, means to hold said plug adjustable in position over said sight 90 hole, said plug having a sight hole therethrough adapted, in one position of the plug, to register with the sight hole in the cap while the plug in other positions serves to close said sight hole in the cap, a sight 95 glass for said plug, and a removable device to hold said glass in position over the sight hole in said plug. 100

4. In a twyer cap having a large clean out opening in its lower portion, a closure therefor, a relatively small sight hole, a sight plug adjustably mounted over said hole and having a sight opening therethrough which in one position of the plug registers with the sight hole in the cap, 110 means to hold said plug against the cap so that in other of its positions it will valve off the sight hole in the cap, a sight glass for the sight opening in the plug, and detachable retaining means for said glass, substantially as described. 115

5. In a twyer cap, a circular internally threaded seat bored in its outer face, said seat having an eccentric sight hole leading through the cap, a sight plug which fits 125 against the inner end of the seat and has a sight opening therethrough, the inner end of which is eccentric to the inner end of the plug and adapted in a predetermined position to register with the sight hole in the 130

cap, a screw stud which turns freely on the plug and is adapted to be screwed into said seat in the cap, a shoulder on the inner end of the plug which is adapted to engage and force the plug against said seat, and means to detachably mount a sight glass on the outer end of the plug, substantially as described.

6. A sight plug having a sight opening which extends longitudinally therethrough and opens through the inner end of the plug at a point eccentric to its longitudinal axis, the inner end of said plug being turned smooth to serve as a valve, and the outer end of said plug having means for the attachment of a glass retaining cap, substantially as described.

7. A sight plug for twyer caps having a sight opening extending longitudinally therethrough and opening through the inner end of the plug to one side of its longitudinal center line, the inner end of the plug adjacent to said opening being turned smooth to serve as a valve, and a glass retaining means screwed on the outer end of said plug and having a central opening aligning with the sight opening in the plug.

8. In an apparatus of the character described, in combination, a cylindrical sight plug having a sight opening extending therethrough, which opening, at its inner end, is eccentric to the long axis of the plug, a shoulder at the inner end of said plug, a stud adapted to slip over the outer end of

the plug with a slip fit and to engage said shoulder on the plug, a detachable glass retaining cap for the outer end of the plug having a sight hole therethrough which aligns with the sight opening in said plug.

9. In an apparatus of the character described, in combination, a twyer cap, a seat bored in its outer face at a slight angle, internal threads in the outer end of said seat, said cap having a sight hole leading eccentrically through said seat, a sight plug, the inner end of which is shouldered and fits rotatably against the bottom of said seat so as to valve off said sight hole in certain positions, an externally threaded stud mounted to turn on said plug and adapted to engage the inner shouldered end of the plug, said stud, when screwed into said threaded seat, being adapted to force the plug against the bottom of said seat, a sight opening extending diagonally through the plug and adapted in one position to register with the sight hole in the cap, a sight glass over the outer end of said sight opening in the plug, and a screw cap having a sight opening in its end and adapted to hold said sight glass on the plug.

In testimony whereof I affix my signature in presence of two witnesses.

KARL LANDGREBE.
